Inventor,
Robert T. Frost, by

G. C. Kennedy,
Attorney.

UNITED STATES PATENT OFFICE.

ROBERT T. FROST, OF ST. PAUL, MINNESOTA, ASSIGNEE OF ONE-HALF TO ALFRED E. JOHNSON, OF WATERLOO, IOWA.

PACKAGE-OPENING MEANS.

1,343,360.

Specification of Letters Patent. Patented June 15, 1920.

Application filed May 22, 1919. Serial No. 298,841.

To all whom it may concern:

Be it known that I, ROBERT T. FROST, a citizen of the United States of America, and a resident of St. Paul, Ramsey county, 5 Minnesota, have invented certain new and useful Improvements in Package-Opening Means, of which the following is a specification.

My invention relates to improvements in 10 package opening means, and the object of my improvement is to supply a device adapted for insertion in a package, associated with certain of the contents thereof, and fastened to lacerable parts of the container, to permit, first, a ready means for 15 opening the package, and second, for withdrawing that part of the contents which is associated therewith, without injury to said contents.

20 This object I have accomplished by the means which is hereinafter described and claimed, and which is illustrated in the accompanying drawings, in which Figures 1, 2 and 3 are like isometric perspective views 25 of a lacerable package, showing in Fig. 1 the filled closed and sealed package supplied with my improved opening means; Fig. 2 showing the package partially opened by said means, and Fig. 3, part of the contents 30 partially withdrawn therefrom by the use of said means. Fig. 4 is an isometric view of a package with a portion of the container removed, to disclose the relative positions therein of the opening means, and Fig. 5 35 is a perspective detail view of said opening means as separated from the package.

In said drawings, similar numerals of reference denote similar parts throughout the several views.

40 I have exemplified my invention in practice as applied to the lacerable container or wrapper 3 of a quantity of cigarettes 5, but it is obvious that my improved opening device may be successfully applied to other 45 descriptions of containers having other or various contents.

The wrapper or container 3 is usually made of thin lacerable paper, its end portions, after the filling is effected, being 50 folded into overlapping flaps 4, which are

then pasted down to close the package and secure the contents from exposure or injury.

When such a package is opened by tearing away a part of said flaps by the fingers, and a withdrawal of one or more of the 55 cigarettes 5 is manually attempted, the fragile covering of the cigarette is often and nearly unavoidably broken. My removing device obviates this.

My said device comprises a small body or 60 plaque 1, which may be of any size or shape desired, or made of any suitable material, but in practice will be formed of cardboard of sufficient rigidity, and having a central orifice through which is passed an end of 65 a flexible device, cord or thread 2, the end part of the latter being then pasted down or secured to the plaque in any desired manner, as by knotting.

The plaque is placed in one end of the 70 bottom of the container 3, and a portion of the contents placed superposed upon it, in this instance, two or more of the cigarettes 5 are placed upon it, and the cord 2 is then extended upwardly between these and the 75 other cigarettes of the package.

The cord 2 is then shaped in a somewhat looped form to follow the angular contour of the end of the container to rest within the inner crease thereof, and its end part 80 is pasted or glued to the inner face of a flap 4, with its extremity only exposed after pasting down of the flap, as shown in said Fig. 1.

The package is opened by grasping the 85 exposed extremity of the cord 2 and placing it under sufficient longitudinal tension to tear the lacerable flap 4 and the wrapper 3 across and around the angle of the latter, thus removing a piece of said flap and 90 wrapper as shown in said Fig. 2.

Continued pulling on the cord 2 then lifts the plaque 1 together with the superincumbent contents of the wrapper, in this case, two or more of the cigarettes 5, as they 95 may have been differently placed thereon, as shown in Figs. 3 and 4, whereby one or more of the cigarettes may be withdrawn without injury. The remainder of the contents of the package may then be removed, 100

after complete withdrawal of the opening device.

Having described my invention, what I claim as new, and desire to secure by Letters Patent, is:

The combination with a container for cigarettes formed of lacerable material one end of which is foldable, of a relatively small plaque therein under part of the ciga-

rettes only, and a string connection between 10 the plaque and the foldable part of the container, fastened along the latter appropriately to tear the latter open when the string connection is placed under endwise tension.

Signed at Waterloo, Iowa, this 5th day of 15 May, 1919.

ROBERT T. FROST.
